(57) **CLAIM**

The ornamental design for a dispenser, as shown and described.

DESCRIPTION

FIG. 1 is a front perspective view of a dispenser according to the present design;

FIG. 2 is a front elevational view thereof;

FIG. 3 is a top view thereof;

FIG. 4 is a bottom view thereof;

FIG. 5 is a first side elevational view thereof; the second side elevational view being a mirror image; and,

FIG. 6 is a back elevational view thereof.

The broken lines shown in the drawings are for illustrative purposes only and form no part of the claimed design.
